FUEL REGULATOR

John B. Hull, Berkeley, Calif., assignor to Westinghouse Pacific Coast Brake Company, Emeryville, Calif., a corporation of California

Application August 4, 1936, Serial No. 94,205

3 Claims. (Cl. 74—107)

This invention relates to control apparatus and more particularly to apparatus adapted to be employed to control the supply of fuel to a furnace.

5 In many furnaces there are provided means responsive to the pressure of the steam in a boiler heated by the furnace for regulating the supply of fuel, such as oil or gas, to the furnace, and for also regulating the position of the draft 10 and damper so as to vary the supply of air to the furnace.

It is desirable that the supply of air be at all 15 times adequate to effect substantially complete combustion of the fuel, but that it does not greatly exceed this amount. It is essential, therefore, that the supply of air and the supply of fuel be simultaneously varied.

In the control systems heretofore provided, the relationship of the position of the fuel supply 20 valve and of the draft and damper have been controlled by adjusting of the length and angles of the levers employed in the control apparatus. However, because of the individual characteristics of different furnaces and stacks, 25 this arrangement did not secure most efficient control of the furnace, and it has been found that if the apparatus were arranged to properly proportion the supply of air and fuel to the furnace at one point in the range of movement of the control apparatus, the control apparatus would not properly proportion the supply of air 30 and fuel to the furnace at other points in the range of movement of the apparatus.

It is the principal object of this invention to 35 provide control apparatus of the type described and incorporating adjustable means by which the relationship between the extent of the opening of the fuel supply valve, and of the draft or damper, may be adjustably varied relative to 40 each other to adapt the control apparatus to the conditions present in the furnace with which the control apparatus is employed.

A further object of the invention is to provide 45 control apparatus of the type described having means for independently varying the relative settings of the fuel supply valve, and of the draft and damper, at a plurality of points throughout the range of movement of the control apparatus.

50 A further object of the invention is to provide an improved control apparatus for varying the supply of fuel to a furnace in response to variations in the pressure of the steam in a boiler heated by the furnace, and incorporating means by which the setting of the fuel supply

valve may be adjustably varied in different positions of the control apparatus independently of the setting of the fuel supply valve in other positions of the control apparatus.

Another object of the invention is to provide 5 a control member having a cam surface thereon, the shape of which may be adjustably varied.

A further object of the invention is to provide an improved control member having a cam surface thereon and incorporating means by which 10 the contour of portions of the cam surface may be adjustably varied independently of the other portions thereof.

Another object of the invention is to provide 15 an improved furnace control apparatus.

Other objects of the invention and features 20 of novelty will be apparent from the following description taken in connection with the accompanying drawings, in which,

Fig. 1 is a diagrammatic view of a furnace 20 equipped with control apparatus provided by this invention.

Fig. 2 is a sectional view of a control device 25 employed in the control apparatus shown in Fig. 1.

Fig. 3 is a view, largely in section, of the valve device employed in the control apparatus shown in Fig. 1 to control the supply of fuel to the furnace, and

Fig. 4 is a fragmentary sectional view taken 30 substantially along the line 4—4 of Fig. 3.

Referring to the drawings, there is illustrated in Fig. 1 thereof a furnace 1, which may be of any well known construction. The furnace 1 has a burner, not shown, which is supplied with 35 fuel through a pipe 2, while the flow of fuel through this pipe is controlled by a valve device indicated generally by the reference numeral 4.

The furnace 1 has a draft door 6 controlling the supply of air to the furnace, while a damper 40 8 is positioned in the smoke pipe 10 leading from the furnace.

A control device, indicated generally by the reference numeral 12 is provided for controlling the draft door 6, the damper 8 and the fuel 45 supply valve device 4. The details of the construction of the control device 12 form no part of the present invention, but I prefer to employ a control device of the type shown and claimed in the application of James W. Harrie, Serial 50 No. 100,311 filed September 11, 1936.

The construction of the control device 12 is best shown in Fig. 2 of the drawings, and, as shown, comprises a movable abutment in the form of a diaphragm 14, which is clamped be- 55

tween confronting flanges on a cover 16 and a body 18, which is supported from the furnace 1 by means of a bracket 19. The diaphragm 14 is subject on one side to the pressure of the fluid in a chamber 20, which is connected by way of a pipe 22 with the boiler, not shown, of the furnace 1. The diaphragm 14 is subject on the other side to a spring 24, which extends between a follower plate 25 and a spring seat 26, which rests upon an adjustable bushing 28.

The diaphragm 14 has secured thereto a stem 30 which engages a face of a lever 32, which has one end thereof pivotally supported on the body 18. The other face of the lever 32 is engaged by the stem 34 of a pilot valve device, indicated generally by the reference numeral 36, for controlling the supply and release of fluid under pressure to and from a chamber 38 on the face of a piston 40, which is reciprocable in a bore 20 in a cylinder 42.

The piston 40 has secured thereto a piston rod 44 which extends through an opening in a cover plate 46, the opening being sealed by means of packing 48, which is held in place by a pack nut 50.

The pilot valve device 36 comprises a ball valve 52, which is mounted in a chamber 54, which is constantly connected by way of the passage and pipe 56 with a source, not shown, of fluid under pressure, such as water under pressure. The ball valve 52 is urged by a spring 58 into engagement with a seat so as to cut off the flow of fluid from the chamber 54 to a chamber 60, which communicates by way of a passage 62 with the chamber 38 at the face of the piston 40.

The stem 34 extends through a chamber 64, which is constantly connected to a drain by means of the passage and pipe 66, which also communicates with the chamber 68 at the upper face of the piston 40. Suitable packing 70 surrounds the stem 34 and is held in place by means of a gland 72, and a packing nut 74, so as to prevent the escape of fluid from the chamber 64 to the atmosphere, while packing 76 surrounds the stem 34 and is held in place by the gland 78 to prevent the flow of fluid from the chamber 60 to the chamber 64. A spring 80 extends between the gland 78 and a spring seat 82 carried by the stem 34 and yieldingly presses the stem 34 against the lever 32.

The stem 34 has a passage 84 formed therein and communicating with the chamber 64, and with a port in the end of the stem which is surrounded by a seat adapted to be engaged by the ball valve element 52.

The control device 12 has associated therewith a bell crank 86, which is pivotally supported on a pin 88. One arm of the bell crank 86 is engaged by a spring seat 90, while a compression spring 92 extends between this spring seat and a seat 94, which engages an adjusting screw 96 carried by the end of the arm 32, and which is held in the adjusted position by a lock nut 98.

The other arm of the bell crank 86 carries a roller 100, while a portion of the body of the control device has mounted thereon adjacent the roller 100, a roller 102. A wedge 104 carried by an arm 105, which is secured to the piston rod 44, extends between the rollers 100 and 102.

The end of the piston rod carries a yoke 106, which is connected by means of a chain 108 with a lever 110, which is pivotally supported intermediate its ends on a pin 112 carried by a bracket 114 mounted on the furnace 1. The lever 110 has secured thereon adjacent the end thereof a

weight 115, which yieldingly urges the lever in a counterclockwise direction, as viewed in the drawings. The lever 110 has secured thereto adjacent the other end thereof a chain 116, which is also connected to the end of the lever 118 for operating the damper 8.

The lever 118 has a weight 120 mounted thereon, which yieldingly urges the lever 118 in a clockwise direction, so as to move the damper 8 to the full open position.

The lever 110 also has secured thereto a chain 122, which is connected to an arm 124 associated with the draft door 6. The draft door 6 is yieldingly urged to the closed position by gravity. In addition the lever 110 has connected thereto at 15 a point on the side of the pin 112 adjacent the chain 108, a link 126 which is connected to an arm 128 of the fuel supply valve device 4.

The construction of the valve device 4 is shown in detail in Figs. 3 and 4 of the drawings, and, 20 as illustrated, comprises a hollow body 130 having flanges 131 and 132 formed integral therewith to which are attached the pipes leading from the source of fuel and to the furnace. The body 130 has a wall 134 extending across the passage 25 therein, and this wall has an opening therein, into which extends a sleeve 136 formed integral with a head 137, which is secured to a flange 138 on the body 130 and closes an opening in the external wall of the body 130. The sleeve 136 30 has a flange 139 formed thereon, and a gasket 140 is clamped between this flange and the wall 134 to prevent unintended flow of fuel from one side of the wall to the other.

The sleeve 136 has a bore therein in which is 35 mounted a piston valve 142 having packing rings 143 fitted thereon. The piston valve 142 controls the flow of fuel from the chamber 144 on one side of the wall 134, to the chamber 145 on the other side thereof through ports 146 in the 40 sleeve 136.

As shown in the drawings, the piston valve 142 is a cup-shaped body having a tubular skirt portion and having a head having a rod 148 formed integral therewith. A passage 150 extends 45 through the head of the piston valve and communicates with the chambers on the opposite sides of the head.

The piston rod 148 extends through an opening in the head 137, and this opening is sealed by means of packing 160, which is held in place 50 by a packing nut 162. A spring 164 extends between the piston valve 142 and the wall of the body 130, and yieldingly urges the piston valve to the upper end of its range of movement so as 55 to fully open the ports 146.

The head 137 has spaced parallel arms 166 formed integral therewith and arranged on opposite sides of the piston rod 148. The upper ends of the arms 166 have pivotally supported 60 thereon a rod 168, and the lever 128 is rigidly secured on the end of the rod 168. The rod 168, in addition, has secured thereto at a point substantially mid-way between the arms 166, a curved member 170.

The piston rod 148 has secured to the upper end thereof a forked member 172 having arms extending along opposite sides of the curved member 170, and these arms have slots 174 formed therein through which extend the rod 168. A 70 shaft 176 is carried by the upper end of the forked member 172, and has a roller 178 mounted thereon intermediate the arms of the forked member 172. The ends of the rod 176 extend through, and are guided by, parallel slots 179 75

formed in the upper ends of the arms 166, while the rod 176 has secured thereon washers 180, which engage the outer faces of the arms 166 to prevent displacement of the rod 176.

- 5 As is best shown in Fig. 3 of the drawings, the member 170 is curved, and the radius of curvature of this member gradually increases away from the rod 168. The curve member 170 has a plurality of threaded holes therein in which are 10 mounted threaded tappets 182, which are held in the adjusted positions by lock nuts 184. The tappets 182 extend through the curved member 170 so that the inner ends thereof may be engaged by the roller 178. The inner ends of the 15 tappets 182 are arranged in substantially the same plane, and are positioned adjacent each other, being spaced apart a distance substantially less than the radius of the roller 178.

The roller 178 is normally held in engagement 20 with the inner ends of the tappets 182 on the curved member 170 by force exerted by the spring 164 through the piston valve 142, the piston rod 148, and the forked member 172 carried thereby.

When the lever 128 and the curved member 170 25 are turned in a counterclockwise direction, as viewed in Fig. 3 of the drawings, the tappets 182 carried by the curved member 170 move across the roller 178 and force the roller downwardly, as the ends of the tappets in the portion of the 30 curved member 170 adjacent the rod 168 are less distant from the axis of the rod 168 about which the curved member 170 is turned, than are the tappets adjacent the free end of the curved member 170.

35 On downward movement of the roller 178, the forked member 172 and the piston rod 148 are moved downwardly, thereby moving the piston valve 142 downwardly against the spring 164 so as to decrease the size of the openings through the 40 ports 146, and thereby decrease the rate of flow of fuel through these ports to the furnace 1.

Likewise when the lever 128 and the curved member 170 are turned in a clockwise direction, as viewed in Fig. 3 of the drawings, the tappets 45 182 move across the roller 178, and, as the tappets in the free end of the curved member 170 are more distant from the axis of the rod 168, about which the member 170 is moved, than are the tappets in the other portion of the member 170, the roller 178 will be moved upwardly by force exerted by 50 the spring 164, with the result that the piston valve 142 will be moved upwardly to increase the size of the openings permitted through the ports 146, and thereby increase the rate of supply of fuel to the burner of the furnace 1.

55 As will be understood the relative size of the openings through the ports 146 permitted by the piston valve 142 in any position of the lever 128, and of the curved member 170, throughout their range of movement, may be adjustably varied by adjusting the position of the tappet or tappets 182 carried by the curved member 170, which are engaged by the roller 178 in this position of the lever 128 and the curved member 170.

60 The curved member 170 is of such shape, and the other portions of the control apparatus are so arranged that the size of the openings through the ports 146 permitted by the piston valve 142 is substantially that required to produce efficient 65 operation of the furnace. The adjustable tappets 182 provide means to vary the size of the openings through the ports 146 of the fuel supply valve device 4 at a plurality of points in the range of movement of the control apparatus. The extent 70 of adjustment permitted by the tappets 182, while

limited, is sufficient to permit the valve device 4 to be adjusted to produce the maximum degree of efficiency of operation of the furnace at the different points throughout the range of movement of the control apparatus.

75 The roller 178, being of substantially larger radius than the distance between adjacent tappets 182, is able to freely move across the ends of the tappets even though there are slight inequalities in the position of the faces of these 10 tappets.

The control apparatus is shown in Fig. 1 of the drawings in the position to condition the fuel supply valve device 4 to supply fuel to the burner of the furnace 1 at a rate approximately intermediate the maximum and minimum rates at which fuel may be supplied thereto, and to maintain the draft door 6 and damper 8 partially open.

At this time, assuming that the pressure of the steam in the boiler heated by this furnace is substantially at the pressure which the control apparatus is adjusted to maintain, the various parts of the control device 12 will be substantially in the position in which they are shown in Fig. 2 of the drawings. In this position of the parts of the 20 control device 12, fluid under pressure is present in the chamber 38 at the face of the piston 40 so as to maintain the piston in the position in which it is shown, while the further supply of fluid to this chamber is cut off as the ball valve 52 is held 25 in the seated position by the spring 58. In addition, the release of fluid from the chamber 38 is cut off as the stem 34 is held in engagement with the ball valve 52 to cut off the flow of fluid from the chamber 60 through the passage 84 in the 30 stem 34.

If the pressure of the steam in the boiler heated by the furnace 1 should for any reason increase to a value above that which the control apparatus is adjusted to maintain, there will be a corresponding increase in the pressure of the fluid in the chamber 20 at the face of the diaphragm 14, and this diaphragm will be moved downwardly 35 against the opposing force of the spring 24, supplemented by the spring 92.

On this movement of the diaphragm 14, the stem 34 will press against the upper face of the lever 32 and cause this lever to press against the end of the stem 34 of the pilot valve device 36, with the result that the end of the stem will press 40 against the ball valve 52 and move the ball valve away from its seat against the spring 58. Fluid supplied by the pipe and passage 56 to the valve chamber 54 then flows to the chamber 60, and thence by way of the passage 62 to the chamber 38 at the face of the piston 40, thereby moving the piston 40 upwardly in the bore in the cylinder 42.

On upward movement of the piston 40 the piston rod 44 is moved upwardly, thereby moving the yoke 106, and its movement is transmitted through the chain 103 to the lever 110 to move this lever in a clockwise direction about the pin 112. This movement of the lever 110 is transmitted through the chain 116 to the lever 118 to move the damper 8 towards the closed position in the smoke pipe 18, while the draft door 6 will be permitted to be moved towards the closed position.

In addition, on this movement of the lever 110 force is exerted through the link 126 to move the lever 128 of the valve device 4 in a counterclockwise direction, as viewed in Figs. 1 and 3 of the drawings, thus moving the curved member 170 so that the tappets 182 carried thereby press upon the roller 178, moving it downwardly, thereby moving the piston valve 142 downwardly to de- 75

crease the size of the openings permitted through the ports 146, and thus decrease the rate of supply of fuel to the burner of the furnace.

In addition, on this upward movement of the piston 40 and piston rod 44, the arm 105 carried by the piston rod 44 will be moved upwardly, thereby moving the wedge 104 between the rollers 100 and 102. On this movement of the wedge 104, the roller 100 is moved to the left, as viewed in Fig. 2 of the drawings, thereby moving the bell crank 86 a short distance in a clockwise direction about the pin 88.

On this movement of the bell crank 86 an arm thereof presses against the spring seat 90 so as to compress the spring 92, and thereby increase the force exerted by this spring on the lever 32 and opposing the force exerted on the lever 32 by the fluid under pressure in the chamber 20 acting through the diaphragm 14 and the stem 30.

As a result of this increase in the force exerted on the lever 32 by the spring 92, the free end of the lever 32 will be moved upwardly, thereby permitting the spring 88 to move the stem 34 of the pilot valve device 36 upwardly. On this upward movement of the stem 34, the ball valve 52 will be moved to its seat by the spring 58.

Fluid under pressure will continue to be supplied to the chamber 38 at the face of the piston 40 to cause upward movement of the piston until the piston has moved far enough in the cylinder 42 to move the wedge 104 between the rollers 100 and 102, and thereby move the bell crank 86 to a position such that the increase in force exerted by the spring 92 on the free end of the lever 32 is great enough to offset the increase in the opposing force exerted on this lever as a result of the increase in the pressure of the steam in the boiler heated by the furnace 1.

When the piston 40 has been moved upwardly substantially this distance, the free end of the lever 32 will have been moved upwardly by the spring 92 an amount sufficient to permit the spring 88 to move the stem 34 of the pilot valve device 36 upwardly far enough to permit the spring 58 to move the ball valve 52 to the seated position to cut off the further supply of fluid to the chamber 38 at the face of the piston 40, and thus cut off upward movement of the piston 40.

As pointed out above, on upward movement of the piston 40, the valve device 4 is operated to restrict the rate of supply of fuel to the furnace 1, while the draft 6 and the damper 8 are moved towards their closed positions, and the extent of change in the adjustment of these members is substantially proportional to the extent of movement of the piston 40 in the cylinder 42.

On a decrease in the pressure of the steam in the boiler heated by the furnace 1 there will be a corresponding decrease in the pressure of the fluid in the chamber 20 on the face of the diaphragm 14, and the diaphragm will be moved upwardly by the spring 24, assisted by the spring 92. On this upward movement of the diaphragm 14, there will be a decrease in the force exerted through the stem 30 on the lever 32, with the result that the spring 88 may move the stem 34 of the pilot valve device 36 upwardly.

On this movement of the stem 34, as the ball valve 52 is held in the seated position by the spring 58 and hence cannot move farther, the end of the stem 34 is moved away from the surface of the ball valve 52 so as to permit communication between the chamber 68 and the passage 84 in the stem 34. Fluid from the chamber 38 at the face 75 of the piston 40 may thereupon escape by way

of the passage 62 to chamber 60, and through the passage 84 to the chamber 64, from which it flows to a suitable drain by way of the passage and pipe 66.

Upon the release of fluid under pressure from the chamber 38, the piston 40 and the piston rod 44 are moved downwardly by the weight 115 carried by the lever 110, assisted by the weight 120 carried by the lever 118. This permits the lever 110 to be moved in a counterclockwise direction 10 about the pin 112, and permits the weight 120 to turn the arm 118 so as to move the damper 8 towards its full open position.

In addition, this movement of the lever 110 is transmitted through the chain 122 to the arm 124 15 associated with the draft door 6 to move the draft door towards its open position.

In addition, on this movement of the lever 110 force is exerted through the link 126 to move the lever 128 in a clockwise direction, as viewed in 20 Figs. 1 and 3 of the drawings, and thereby move the curved member 170 in a clockwise direction. On this movement of the curved member 170 the tappets 182 carried thereby are moved across the face of the roller 178 so that the roller is successively engaged by the ends of tappets which are farther removed radially from the axis about which the member 170 is turned.

On this movement of the curved member 170, the piston valve 142 is moved upwardly by the 30 spring 164 so as to maintain the roller 178 in engagement with the ends of the tappets 182, and on this movement of the piston valve 142 the size of the openings through the ports 146 is increased, thereby permitting an increase in the rate of supply of fuel to the furnace.

It will be seen, therefore, that on downward movement of the piston 40, the draft 6 and the damper 8 are opened, and at the same time the valve device 4 is conditioned to increase the supply of fuel to the furnace burner.

In addition, on this downward movement of the piston 40, the wedge 104 carried by the arm 105 secured to the piston rod 44 is moved downwardly between the rollers 100 and 102, and on this movement of the wedge 104, the bell crank 86 is moved by the spring 92 so as to maintain the roller 100 in engagement with the wedge 104, while the spring 92 expands, thereby reducing the force exerted by this spring on the end of the lever 32. 50 This results in a reduction in the force exerted by the spring 92 through the lever 32 and the stem 30 on the diaphragm 14. When this force has been reduced by an amount corresponding to the reduction in the opposing force exerted on the diaphragm 14 as a result of the reduction in the pressure of the steam in the boiler, the diaphragm 14 will be moved downwardly by the fluid under pressure in the chamber 20, and this movement will be transmitted through the stem 30 to the lever 32 to press this lever against the end of the stem 34 of the pilot valve device 36.

On downward movement of the stem 34 against the opposing force of the spring 88, the end of the stem is gradually moved adjacent the face of the ball valve 52 so as to reduce the rate of flow of fluid under pressure from the chamber 38 at the face of the piston 40, and eventually the end of the stem 34 is moved into engagement with the 70 ball valve 52 so as to cut off the flow of fluid from the chamber 38 to the passage 34 in the stem 34, through the chamber 64, and thence to the drain by way of the passage and pipe 66. The ball valve 52 is held in the seated position by the spring 58. 75

When the release of fluid from the chamber 38 is cut off, further downward movement of the piston 40 is prevented.

The amount of downward movement of the piston 40 which occurs before the release of fluid from the chamber 38 is cut off is such as to move the wedge 104 downwardly a distance sufficient to permit the bell crank 86 to be moved by the spring 92 so that the reduction in the force exerted by the spring 92 on the lever 32, and thereby on the diaphragm 14, is substantially equal to the reduction in force exerted on the diaphragm 14 by the fluid in the chamber 20 as a result of the reduction in the pressure of the steam in the boiler of the furnace 1.

On each subsequent change in the pressure of the steam in the boiler of the furnace controlled by this control apparatus, the control device 12 operates in the manner described in detail above to vary the setting of the valve device 4, which controls the supply of fuel to the furnace burner, and also to vary the setting of the draft door 6 and the damper 8, which control the supply of air to the furnace fire box.

The relative changes in the settings of these members which occur as a result of operation of the control device 12 may be adjustably varied by changing the points of connection of the link 126, and of the chains 116 and 122, with the lever 110, and with the members 128, 118 and 124, respectively. This permits the rate of supply of fuel and air to the furnace to be proportioned throughout the entire range of movement of the control apparatus so as to be substantially in the proportion required to effect complete combustion of the fuel.

However, due to the peculiarities of various furnaces, if the setting of the fuel supply valve device 4, and the draft door 6 and damper 8, are simultaneously varied to the same extent, the relationship of the rate of supply of fuel and of air to the furnace will not be such as to provide for most efficient combustion of the fuel throughout the entire range of movement of the control apparatus.

It has been found if the elements of the control apparatus are arranged so that the setting of the fuel supply valve device 4 and of the draft and damper are adjusted to give proper combustion of the fuel at one point in the range of movement of the control apparatus, that they will not operate to produce the proper adjustment of these members at other points in the range of movement of the control apparatus, and, as a result, the most efficient and complete combustion of the fuel throughout the entire range of movement of the control apparatus has not been secured.

The control apparatus provided by this invention incorporates means by which the setting of the valve device 4 may be adjustably varied at a plurality of points throughout the range of movement of the control apparatus, so that the relative settings of the valve device 4, and of the draft and damper, may be adjustably varied to produce most efficient combustion of the fuel throughout the entire range of movement of the control apparatus.

If it is found at any point in the range of movement of the control apparatus that the relationship of the rate of supply of fuel and air are not such as to produce most efficient combustion of the fuel, the rate of supply of fuel may be changed by adjusting the tappet or tappets 182 engaged by the roller 178 at this point in the

range of movement of the control apparatus to thereby alter the position of the piston valve 142 and thus change the size of the openings through the ports 146, and accordingly the rate of supply of fuel to the furnace burner.

In this manner the supply of fuel may be controlled so as to produce the most efficient combustion of the fuel at this point in the range of movement of the control apparatus, while the supply of fuel may be similarly regulated at other points in the range of movement of the control apparatus, and thus properly proportion the supply of fuel and air to the furnace throughout the entire range of movement of the control apparatus.

While one embodiment of the improved control apparatus provided by my invention has been illustrated and described in detail, it should be understood that the invention is not limited to these details of construction, and that numerous changes and modifications may be made without departing from the scope of the following claims.

Having now described my invention, what I claim as new and desire to secure by Letters Patent, is:

1. In a control apparatus, in combination, a shaft pivotally supported, a member carried by said shaft and having a portion curved in a plane perpendicular to the axis of the said shaft, the distance from the axis of the shaft to the adjacent face of said portion gradually changing throughout the extent of said portion, a plurality of elements extending through said portion of said member and adjustable relative thereto in the plane in which said portion is curved, the ends of said elements projecting from the face of said portion remote from the axis of said shaft carrying means for adjusting said elements relative to said member, the ends of said elements projecting from the face of said portion adjacent the axis of said shaft cooperating to form an operating surface, and a member adapted to engage said operating surface.

2. In a control apparatus, in combination, a shaft pivotally supported, a member carried by

45 said shaft and having a portion curved in a plane perpendicular to the axis of the said shaft, the distance from the axis of the shaft to the adjacent face of said portion gradually changing throughout the extent of said portion, a plurality of elements extending through said portion of said member and adjustable relative thereto in the plane in which said portion is curved,

30 the ends of said elements projecting from the face of said portion remote from the axis of said shaft carrying means for adjusting said elements relative to said member, the ends of said elements projecting from the face of said portion adjacent the axis of said shaft cooperating to form an operating surface, and a member adapted to engage said operating surface.

3. In a control apparatus, in combination, a shaft pivotally supported, a member carried by

45 said shaft and having a portion curved in a plane perpendicular to the axis of the said shaft, the distance from the axis of the shaft to the adjacent face of said portion gradually changing throughout the extent of said portion, a plurality of elements extending through said portion of said member and adjustable relative thereto in the plane in which said portion is curved,

50 the ends of said elements projecting from the face of said portion remote from the axis of said shaft carrying means for adjusting said elements relative to said member, the ends of said elements also carrying means cooperating with said member for locking said elements in their adjusted positions, the ends of said elements projecting from the face of said portion adjacent the axis of said shaft cooperating to form an operating surface, and a member adapted to engage said operating surface.

4. In a control apparatus, in combination, a shaft pivotally supported, a member carried by

45 said shaft and having a portion curved in a plane perpendicular to the axis of the said shaft, the distance from the axis of the shaft to the adjacent face of said portion gradually changing throughout the extent of said portion, a plurality of elements extending through said portion of said member and adjustable relative thereto in the plane in which said portion is curved,

50 the ends of said elements projecting from the face of said portion adjacent the axis of said shaft cooperating to form an operating surface, and a member adapted to engage said operating surface.

5. In a control apparatus, in combination, a shaft pivotally supported, a member carried by

45 said shaft and having a portion curved in a plane perpendicular to the axis of the said shaft, the distance from the axis of the shaft to the adjacent face of said portion gradually changing throughout the extent of said portion, a plurality of elements extending through said portion of said member and adjustable relative thereto in the plane in which said portion is curved,

55 the ends of said elements projecting from the face of said portion adjacent the axis of said shaft cooperating to form an operating surface, and a member adapted to engage said operating surface.

6. In a control apparatus, in combination, a shaft pivotally supported, a member carried by

45 said shaft and having a portion curved in a plane perpendicular to the axis of the said shaft, the distance from the axis of the shaft to the adjacent face of said portion gradually changing throughout the extent of said portion, a plurality of elements extending through said portion of said member and adjustable relative thereto in the plane in which said portion is curved,

60 the ends of said elements projecting from the face of said portion adjacent the axis of said shaft cooperating to form an operating surface, and a member adapted to engage said operating surface.

7. In a control apparatus, in combination, a shaft pivotally supported, a member carried by

the face of said portion remote from the axis of said shaft carrying means for adjusting said elements relative to said member, the ends of said elements projecting from the face of said portion adjacent the axis of said shaft cooper-
5 ing to form an operating surface, and a member

carrying a roller adapted to engage the operat-
ing surface formed by said elements, the radius
of said roller being substantially greater than
the distance which the ends of said elements are
spaced apart.

JOHN B. HULL.
